(57) **CLAIM**

The ornamental design for a control device, as shown and described.

DESCRIPTION

FIG. 1 is a front elevational view of an ornamental design for a control device in a first configuration;

FIG. 2 is a rear elevational view of the control device of FIG. 1;

FIG. 3 is a top plan view of the control device of FIG. 1;

FIG. 4 is a bottom plan view of the control device of FIG. 1;

FIG. 5 is a right side elevational view of the control device of FIG. 1;

FIG. 6 is a left side elevational view of the control device of FIG. 1;

FIG. 7 is a perspective view of a front, top, and left side of the control device of FIG. 1;

FIG. 8 is a perspective view of a rear, top, and right side of the control device of FIG. 1; and,

FIG. 9 is a perspective view of a front, top, and right side of the control device of FIG. 1 in a second configuration.

1 Claim, 8 Drawing Sheets
